US0D1042413S

(12) **United States Design Patent** (10) Patent No.: **US D1,042,413 S**
(45) Date of Patent: ** Sep. 17, 2024

(54) **WIRELESS HEADSET**

(71) Applicant: **Xueqing Deng**, DongGuan (CN)

(72) Inventor: **Xueqing Deng**, DongGuan (CN)

(**) Term: **15 Years**

(21) Appl. No.: **29/871,409**

(22) Filed: **Feb. 20, 2023**

(51) LOC (14) Cl. **14-01**

(52) U.S. Cl.

USPC **D14/223**

(58) **Field of Classification Search**

(57) **CLAIM**

I claim the ornamental design for the wireless headset, as shown and described.

DESCRIPTION

FIG. 1 is a top, front, left perspective view of a wireless headset of my new design;

FIG. 2 is a bottom, rear, right side perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the figures depict portions of the wireless headset that form no part of the claimed design.

1 Claim, 8 Drawing Sheets
